Primary Examiner — Kevin Rudzinski*Assistant Examiner* — Kathleen Jones(74) *Attorney, Agent, or Firm* — McAndrews Held & Malloy, Ltd.(57) **CLAIM**

The ornamental design for a display screen or portion thereof with icon, as shown and described.

DESCRIPTION

FIG. 1 is a front view of a display screen or portion thereof with icon showing our new design; and, FIG. 2 is an enlarged view thereof, shown separately for clarity of illustration.

The outer perimeter illustrated by a pair of broken lines in FIG. 1 represents a display screen or portion thereof and forms no part of the claimed design.
